BADGE OR SIMILAR ARTICLE

Millard Joseph Hines, St. Petersburg, Fla.
Application March 25, 1954, Serial No. 29,695

Term of patent 14 years
(Cl. D29—2)

FIG. 1

FIG. 3

Fig. 1 is a front elevational view of a badge or similar article showing my new design;

Fig. 2 is a rear elevational view thereof; and

Fig. 3 is a side elevational view thereof.

I claim:

The ornamental design for a badge or similar article, as shown.
